TOILET SET HANDLE FOR MIRROR AND
BACK CONSTRUCTION

William Steinen, Newark, N. J.

Application July 15, 1948, Serial No. 38,853

1 Claim. (Cl. 88—102)

1

The present invention relates to an implement construction and it particularly relates to an implement to be utilized in connection with toilet set implements.

Although not specifically limited thereto, the present invention will be particularly described in its application to hand mirrors. It is to be understood, however, that it is also applicable to hand brushes, hand files and in general to other hand implements in which it is desirable to have a light, compact and durable construction.

It is among the objects of the present invention to provide a novel handle construction generally useful for light-weight implements and particularly useful in connection with toilet-set articles, such as mirrors, hand brushes and hand files, which will be durable, will not readily separate and which may be readily manufactured at low cost.

Another object is to provide an improved handle construction particularly adapted to hand mirrors and hand brushes in which assurance will be had of substantially permanent connection between the handle and the mirror or brush without necessity of using screws, bolts, threaded rods or complicated connection arrangements.

Another object is to provide a new handle construction which will permit such implements as hand mirrors and hand brushes to be readily attached to hollow handles of a wide variety of constructions, shapes and forms, whether of plastic or metal, with assurance that there will be no separation over relatively long periods of rigorous usage.

Still further objects and advantages will appear in the more detailed description set forth below, it being understood, however, that this more detailed description is given by way of illustration and explanation only and not by way of limitation, since various changes therein may be made by those skilled in the art without departing from the scope and spirit of the present invention.

In accomplishing the above objects, it has been found most satisfactory to provide a backing plate in the mirror, brush or other article to be attached to the head of the handle and also to provide a bow member or U member of round wire, the upper ends of the legs of which are spot-welded to the head of the handle.

The handle, on the other hand, is provided with an elongated recess longitudinally thereof which is designed to receive said bowed handle member. The bowed wire member by friction or by gripping teeth, when forced into the cavity or recess of the

2

handle, will be retained substantially permanently in position therein.

With the foregoing and other objects in view, the invention consists of the novel construction, combination and arrangement of parts as hereinafter more specifically described, and illustrated in the accompanying drawings, wherein is shown an embodiment of the invention, but it is to be understood that changes, variations and modifications can be resorted to which fall within the scope of the claim hereunto appended.

In the drawings wherein like reference characters denote corresponding parts throughout the several views:

15 Fig. 1 is a front elevational view, partly in section, of a hand mirror showing the application of the present invention, with the handle and the attachment of the handle being shown in section and with the left side of the mirror broken away.

20 Fig. 2 is a fragmentary longitudinal transverse vertical sectional view upon the line 2—2 of Fig. 1.

Fig. 3 is a transverse horizontal sectional view upon the line 3—3 of Fig. 1.

25 Fig. 4 is an enlarged diagrammatic fragmentary side view of an alternative form of handle insert, showing the provision of gripping teeth on the exterior sides of the bowed handle insert member.

30 Referring to Figs. 1 and 2, there is shown a mirror 10 with the bevelled edges 11 and the rim 12. The edges 11 and rim 12 are retained by the channel member 13 extending around the entire periphery thereof.

35 In back of the mirror 10 is the backing felt material 14, which is compressed by the metal backing plate 15 (see Fig. 2). The plate 15 has substantially the same contour as the mirror 10. The backing plate has a decorative back 16. The decorative back 16 is also held in position by the channel member 13 at its periphery 17.

The backing plate 15 has a cut-out portion 18. At the lower edge of the cut-out 18 the bowed handle extension member 19 is attached.

40 The bowed handle member 19 may consist of a U-bent piece of round wire or square wire and the ends 20 are flattened and spot welded, as indicated at 21, to the backing plate 15.

The sides 22 terminate in the bottom bend 23 and usually have sufficient resiliency so as tightly to grip the sides 24 of the cavity 25 in the handle 26.

45 The upper part of the cavity flares both laterally and transversely, as indicated at 27, to receive the collar 28. The collar 28 has an en-

larged lower portion 29 and a sleeve extension 30. As indicated best in Fig. 1, the U channel 13 has its side flanges cut off at 31 while the bottom 32 continues, as indicated at 33, along the side of the upper portions 34 of the bowed member 19 and down through the collar 28. This collar 28 holds the channel rim 13 together and draws it tightly around the mirror 10, the soft felt backing 14, the steel backing plate 15, and the decorative backing sheet 16.

In the alternative form as shown in Fig. 4, the bows 22 of the member 19 may be provided with teeth 35 having the sloping inlet edges 36 which permit the bowed member 19 to be forced into the cavity 25 and the locking edges 37 which hold it against separation.

The handle 26 may be of metal or plastic and the bowed member 19 may be made of stainless steel or other resilient materials. It may even be made of plastic materials and in such case the handle member 19 should be provided with the gripping teeth 35, as indicated in Fig. 4.

There is thus provided a simple, durable, inexpensive relative handle insert for handles of toilet set implements which will not separate during usage and which will be most readily assembled.

While there has been herein described a preferred form of the invention, it should be understood that the same may be altered in details and in relative arrangement of parts within the scope of the appended claim.

Having now particularly described and ascertained the nature of the invention, and in what manner the same is to be performed, what is claimed is:

5 A toilet set handle construction for a mirror having a metal back or the like comprising an elongated handle member having an elongated recess with curved downwardly converging interior sides and an outward flare at the open inner end thereof and an elongated U-shaped insert to be forced in said recess composed of a U-shaped round wire member with the legs bowed outwardly and coming closely together adjacent the mirror and adjacent the bottom of the recess, the outwardly bowed portions of the legs at their points of maximum separation being serrated.
